H. A. POPPENHUSEN

FUEL RETARDING MEMBER

Filed Dec. 22, 1919

UNITED STATES PATENT OFFICE.

HERMAN A. POPPENHUSEN, OF HAMMOND, INDIANA, ASSIGNOR TO GREEN ENGINEERING COMPANY, OF EAST CHICAGO, INDIANA, A CORPORATION OF ILLINOIS.

FUEL-RETARDING MEMBER.

Application filed December 22, 1919. Serial No. 346,472.

To all whom it may concern:

Be it known that I, HERMAN A. POPPENHUSEN, a citizen of the United States, residing at Hammond, in the county of Lake 5 and State of Indiana, have invented new and useful Improvements in Fuel-Retarding Members, of which the following is a specification.

This invention relates to fuel retarding 10 members for furnaces of that type having traveling grates.

Among the objects of my invention is to construct such member so that it may be water or liquid cooled and thus have its temperature 15 reduced below that of the hot ash and clinkers, which move against it, to prevent adhesion and accretion of the same thereto. A further object is to mount the fuel retarding member so that the same may 20 be adjusted vertically toward or from the fuel supporting surface of the grate in a plane substantially at right-angles to said surface and thus vary the height of the discharge passage for the ash between the same 25 and the grate.

The invention consists further in the matters hereinafter described and more particularly pointed out in the appended claims.

In the accompanying drawings

30 Fig. 1 is a longitudinal vertical sectional view taken through the rear portion of the combustion chamber of a furnace, and showing a fuel retarding member of my invention located above the grate adjacent its rear end and between the same and the bridge wall overhang;

Fig. 2 is a horizontal sectional view taken on line 2—2 of Fig. 1;

Fig. 3 is a vertical sectional view taken on line 3—3 of Fig. 2; and

Figs. 4 and 5 show details of construction to be hereinafter described.

In the drawings, 1, 1 indicate the side walls of the furnace, 2 the bridge wall, 3 the endless chain grate, and 4 the bridge wall overhang, which extends forward over and above the rear end of the grate in furnaces of this general type. There is also a water back pipe 5 above the grate and beneath the forward edge of the bridge wall overhang, as shown.

The fuel retarding member 6 of my invention is located above the grate 3 adjacent its

rear end and between the same and the bridge wall overhang 4 at a point in advance of the place where the ash or consumed fuel is discharged by the grate over its rear end. In the type of structure shown, the fuel retarding member 6 is also to the rear of the water back pipe 5, and said member 6 extends across the grate 3 between the side walls 1, 1, as shown in Fig. 2. Said member 6 is so made that it may be water or liquid cooled, and is so mounted that it may be adjusted vertically toward or from the grate 65 for the purpose heretofore stated.

As shown, said member 6, for the purpose of convenient installation, handling, and repair, is made of a plurality of like, separate sections 7, 7. Each section is hollow and is 70 divided into two separate compartments or chambers by a partition wall 8. The sections 7 are arranged end to end and each has a rear web or flange 9. Said sections are connected together and maintained in rigid end-wise alignment by a connecting bar 10, which extends lengthwise of the aligned sections to the rear thereof, and secured by fastening members 11 to the webs 9, as shown in Figs. 2 and 5. Extending between 80 the side walls 1, 1 to the rear of the member 6, is a rock shaft, in the form of a pipe 12, to which the member 6 is connected by a plurality of arms 13, 13, one for each section 7. Said arms 13 have their forward ends secured by fastening members 14 to the bar 10, and their inner ends attached to the pipe 12 by a two-part clamp, one part 15 being carried at the rear end of the arm and the free part 16 secured to the first part about the 90 pipe by clamp bolts 17, as shown in Fig. 1.

By rocking the pipe 12, the fuel retarding member 6 may be adjusted or moved vertically toward or from the fuel supporting surface of the grate 3, in a plane substantially at right-angles to said grate, and to do this manually any suitable form of mechanism may be employed. One form is shown in the drawings, and it comprises an arm 18 attached by a split clamp 19 to one end of the pipe 12. A counter-weight 20 is mounted on said arm and the clamp 19 has another arm 21 carrying a pin 22 to enter any one of a number of circumferentially arranged holes 23 in a plate 24 held in fixed position 100 against the adjacent side wall 1. This con-

struction is preferably arranged outside of the furnace, to be conveniently reached and operated, and by the pin 22, the member 6 may be held in any position of its adjustment.

To circulate a flow of cooling water or other liquid through the hollow sections 7, 7, the upper chambers of said sections are connected by pipes or conduits 25 arranged 10 at the rear of the sections and extending across the intervals of space between them, as shown. The lower chambers are connected in like manner by pipes 26, and the upper and lower chambers of one of the end 15 sections are connected by a pipe 27 to secure a return, as shown in Figs. 2 and 3. To the opposite end section 7 are connected the supply and outlet pipes 28, 29, the former opening into the upper chamber and the latter into the lower chamber of that section. The pipes 28, 29 extend through the adjacent 20 side wall 1 and are suitably coupled to the cooling water supply and discharge pipes, respectively. By the arrangement shown 25 and described, a continuous flow or circulation of cooling water or other liquid may be maintained through the fuel retarding member 6, although made in separate sections, and thus the temperature thereof reduced 30 below that of the hot ash and clinkers, to prevent adhesion and accretion of the same to the fuel retarding member.

To allow the inlet and discharge pipes 28, 29 to move with the member 6 when adjusted vertically, said pipes extend through 35 an arcuate slot 30 in the side wall, and said slot is closed on the outside by an arcuate plate 32, the pipes extending through the plate and the latter being connected with the 40 arm 21, which may have a handle 31 to be grasped in adjusting the member 6. As shown in the drawings, the sections 7 are box-like in shape, although they may be made in other shapes when required. The 45 range of vertical adjustment of the member 6 is indicated by the full and dotted lines in Fig. 1.

I claim as my invention:

1. In a furnace, the combination of a 50 combustion chamber, a traveling grate therein, a liquid cooled fuel retarding member above said grate adjacent the rear end thereof and extending across the same, said member being formed of a plurality of separate hollow sections arranged end to end, means 55 providing communication between said sections so that a cooling liquid may be circulated through said member from one section to the other, each section having a rear web, 60 a bar extending lengthwise of said member to the rear thereof and secured to said webs, a rock shaft spaced rearward of said sections, arms extending between said bar and said shaft and connected therewith for supporting and adjusting said sections toward 65

and from said grate, and means for turning said shaft and holding said member in any of its adjusted positions.

2. In a furnace, the combination of a combustion chamber, a traveling grate therein, 70 a fuel retarding member above said grate adjacent the rear end thereof and extending across the same, said member being formed of a plurality of separate hollow sections arranged end to end, means connecting said sections together and maintaining the same in endwise alignment, means providing communication between said sections so that a cooling liquid may be circulated through said member from one section to the other, and means to the rear of said sections and pivoted to fixed parts of the furnace structure and connected with said sections for supporting and adjusting the same toward and from 80 said grate and resisting the thrust of the fuel bed against said sections.

3. In a furnace, the combination of a combustion chamber, a traveling grate therein, a bridge wall at the inner end of said grate and spaced rearward therefrom, said bridge wall having a portion overhanging the rear end of said grate, a fixed water back and a liquid cooled fuel retarding member extending across the grate above the same and located between the grate and said overhang, 90 said fuel retarding member being spaced rearward from said water back, said member being formed of a plurality of separate hollow sections arranged end to end, means connecting said sections together and maintaining the same in endwise alignment, 95 means providing communication between said sections so that a cooling liquid may be circulated through said member from one section to the other, and means pivoted to the side walls of the combustion chamber to the rear of said sections and connected therewith for supporting and adjusting said member toward and from said grate and resisting the thrust of the fuel bed against 100 said sections.

4. In a furnace, the combination of a combustion chamber, having side walls, a traveling grate therein, a liquid cooled fuel retarding member above said grate adjacent the rear end thereof and extending across the same, said member terminating short of 115 said side walls, said member being formed of a plurality of separate hollow sections arranged end to end, means connecting said sections together and maintaining the same in endwise alignment, means providing communication between said sections so that a cooling liquid may be circulated 120 through said member from one section to the other, inlet and outlet pipes connected with a section at one end of the member and extending outward through an arc-shaped slot in the adjacent side wall, and means to the 125 rear of said sections and pivoted to fixed 130

parts of the furnace structure and connected with said sections for supporting and adjusting the same toward and from said grate and resisting the thrust of the fuel bed against said sections.

5. In a furnace, the combination of a combustion chamber, a traveling grate therein, a bridge wall at the inner end of said grate and spaced rearward therefrom, said bridge 10 wall having a portion overhanging the rear end of said grate, a fixed water back extending across said grate beneath said overhang and supporting the latter, a liquid cooled fuel retarding member extending across said 15 grate between the same and said overhang and to the rear of said water back, said member being formed of a plurality of sepa-

rate hollow sections arranged end to end and in communication with each other so that a cooling liquid may be circulated therethrough, means connecting said sections together and maintaining the same in endwise alignment, and means to the rear of said sections and pivoted to parts of the furnace structure other than said overhang and connected with said sections for supporting and adjusting the same toward and from said grate and resisting the thrust of the fuel bed against said sections.

20 In testimony that I claim the foregoing as 30 my invention, I affix my signature, this 17th day of December, A. D. 1919.

HERMAN A. POPPENHUSEN.
